UNITED STATES PATENT OFFICE.

EDGAR N. SPAULDING AND RALPH E. SPAULDING, OF SUFFIELD, CONNECTICUT.

STEEL GIRDER-FRAME FOR REINFORCED-CONCRETE GIRDERS.

No. 887,863.

Specification of Letters Patent.

Patented May 19, 1908.

Application filed July 26, 1907. Serial No. 365,763.

To all whom it may concern:

Be it known that we, EDGAR NATHAN SPAULDING and RALPH EDGAR SPAULDING, both citizens of the United States, and residents of Suffield, in the county of Hartford and State of Connecticut, have invented a new and useful Steel Girder-Frame for Reinforced-Concrete Girders, of which the following is a specification.

Our invention relates to improvements in steel reinforcement frames for concrete girders, in which we use combination shear and tension bars of peculiar formation to unite a central longitudinal top stay bar with two longitudinal bottom tension bars, and also employ inclined tie braces, the latter being at the ends of said longitudinal bars, all as hereinafter set forth.

The objects of our invention are, first, to produce a triangular frame, of the class specified, in which the amount of steel used in its construction is minimized by so distributing or placing it that there is the most steel where the greatest load is sustained, the amount of steel decreasing as the load to be carried thereby decreases; second, to utilize the same member in such a frame for both shear and tension, such member consisting of a twisted flat bar of special construction, and, third, to provide a frame which is adapted to support twisted steel floor rods, wire cloth, expanded metal, etc., when used in connection with reinforced floors, thus making a unit system of reinforced floor construction.

Our frame is adaptable to girders of any size and of any required strength and offers the least possible obstruction in the filling form to the concrete.

We attain the objects and secure the advantages above pointed out by the means illustrated in the accompanying drawings, in which—

Figure 1 is a top view of a frame embodying our invention; Fig. 2, a side elevation of said frame; Fig. 3, an end elevation of the same, and, Fig. 4, a cross-section taken at the center of the frame.

Similar letters refer to similar parts throughout the several views.

Referring to the drawings it will be observed that the frame therein shown is made up of two bottom tension bars *a* and a top stay bar *b* extending the entire length of the frame, said bar *b* being remote from but parallel with said bars *a* and centrally placed relative

thereto, flat bars *c* fastened by pinch clips *a* to the bars *a* and riveted at *e* to the bar *b*, and triangular end pieces or tie braces *f* connecting the ends of the aforesaid bars *a* and *b*. Each end piece or brace *f* is twisted between the bars *a*, as shown in Fig. 3. Said braces are riveted to the bars *a* and *b*, a brace at each end of said bars, and these members produce a frame of triangular construction or formation. Holes *g* are made in the bar *b* for the accommodation of rods used for floor slab reinforcement.

The bars *c* are arranged in pairs, and the shortest pair is in the center, then comes a longer pair, and finally a still longer pair, three pairs in all, although this number may vary. Each of these pairs has a horizontal part and is bent upward, outward and toward the longitudinal central plane of the frame at the terminals and twisted as shown. The bars are twisted in order to facilitate bending into position and for the purpose of affording a good grip or anchorage for the concrete. There is one full twist in each of the oblique terminals or parts of each bar *c*. The horizontal parts of the longest pair of bars *c* lie against the inside faces of the bars *a*, corresponding parts of the intermediate pair lie against the inside faces of the first-mentioned horizontal parts, and the corresponding parts of the shortest pair lie against the inside faces of the intermediate horizontal parts, and the clips *d* secure the several horizontal contiguous members on each side of the frame together. The upper ends of all the bars *c* are riveted to the bar *b*, as already noted, those on one side of the frame being fastened to said bar *b* on the same side thereof, and those on the opposite side of the frame being fastened to said bar *b* on the opposite side thereof. It will readily be understood that the members *c* constitute combination shear and tension bars which are eminently suited to reinforcing frames.

It is clear from the foregoing that the combined and united tension members in the center of the frame at the bottom present most steel in cross-section and consequently afford the maximum amount of strength at the place where it is required, and the power of resistance of the frame grows less from the central portion outward towards the ends thereof as the number of such tension members decreases. In other words, the strength of the frame gradually decreases in propor-

tion to the decrease in the load which it is calculated to sustain, from the maximum at the center to the minimum at the ends.

By providing more than one bottom tension bar on a side and more than one upper stay bar a frame can be produced which is capable of taking the place of I-beams in girders which have little depth and are of narrow breadth.

10 What we claim as our invention, and desire to secure by Letters Patent, is—

15 1. A girder frame, of the class described, comprising bottom tension members spaced apart, a top stay member, combination shear and tension members structurally independent and separate from each other and from the bottom tension members, of unequal lengths, and having oblique terminals, the horizontal portions of said combination shear 20 and tension members on each side and the corresponding bottom tension member being side by side and in contact with each other, means to fasten such contacting horizontal parts together, and means to fasten the free 25 ends of said oblique terminals to said top stay member.

30 2. A girder frame, of the class described, comprising bottom tension members spaced apart, a top stay member, combination shear and tension members of unequal lengths and having twisted oblique terminals, the horizontal portions of said combination shear and tension members on each side and the corresponding bottom tension member being arranged side by side and in contact with each other, means to fasten such contacting horizontal parts together, and means to fasten the free ends of said twisted oblique terminals to said top stay member.

35 40 45 3. A girder frame, of the class described, comprising bottom tension members spaced apart, a top stay member, combination shear and tension members structurally independent and separate from each other and from the bottom tension members arranged in pairs of unequal lengths and having oblique terminals, the horizontal portions of said combination shear and tension members on each side and the corresponding bottom ten-

50 sion member being arranged side by side and in contact with each other, means to fasten such contacting horizontal parts together, and means to fasten the free ends of said oblique terminals to the sides of said top stay member.

55 4. A girder frame, of the class described, comprising bottom tension members spaced apart, a top stay member, combination shear and tension members arranged in pairs of unequal lengths and having oblique terminals, the horizontal portions of said combination shear and tension members on each side and the corresponding bottom tension member being arranged side by side and in contact with each other, means to fasten such horizontal contacting parts together, means to fasten the free ends of said oblique terminals to said top stay member, and inclined tie braces connecting the tension and stay members.

60 65 70 75 5. A girder frame, of the class described, comprising bottom tension members spaced apart, a top stay member, combination shear and tension members having oblique terminals, said combination shear and tension members connecting the top stay member with the bottom tension members, and triangular end pieces or tie braces connecting the bottom tension members with the stay member and with each other.

80 85 90 6. A girder frame, of the class described, comprising bottom tension members spaced apart, a top stay member, combination shear and tension members having oblique terminals, said combination shear and tension members connecting the top stay member with the bottom tension members, and triangular end pieces or tie braces connecting the bottom tension members with the stay member and with each other, each of such braces having a twist therein between the bottom tension members.
